UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PA., A CORPORATION OF PENNSYLVANIA.

RAILWAY-TRAFFIC-CONTROLLING APPARATUS.

Application filed July 15, 1919. Serial No. 311,015.

To all whom it may concern:

Be it known that I, RONALD A. McCANN, a citizen of the United States, residing at Swissvale, in the county of Allegheny and State of Pennsylvania, have invented certain new and useful Improvements in Railway-Traffic-Controlling Apparatus, of which the following is a specification.

My invention relates to railway traffic controlling systems, and particularly to systems of the type comprising traffic controlling devices, such for example as ramps, located at intervals in the trackway and each arranged to co-operate with train carried governing apparatus to cause one of a plurality of different indications aboard the train according to the electrical condition of the trackway device. More specifically, my invention relates to trackway apparatus for systems of this character suitable for use on stretches of single track over which traffic moves in both directions.

I will describe one form of trackway apparatus embodying my invention, and will then point out the novel features thereof in claims.

In the accompanying drawings, Figs. 1^a, 1^b, 1^c and 1^d are diagrammatic views showing one form of trackway apparatus embodying my invention, it being understood that a complete system is formed by placing these views together end to end in the order named.

Referring to the drawings, the reference characters 2 and 2^a designate the track rails of a single track over which traffic moves in both directions. The stretch of track here shown includes one passing siding G and part of another passing siding H. The rails are divided by insulated joints 3 into a plurality of track sections 4—5, 5—6, * * * 12—13, and each section is provided with a track circuit comprising a track battery b, the rails of the section, and one or more track relays each of which is designated by the reference character T with a suitable exponent. In the case of each section except section 9—10, a track battery is located at one end of the section and a track relay at the other; the track circuit for section 9—10 is arranged with a track battery at the middle of the section and two track relays T⁶ and T⁷ one at each end.

Traffic along the stretch from west to east is governed by a plurality of roadside sig-

nals S', S⁵, S⁶ and S⁷, while traffic along the stretch from east to west is governed by a plurality of signals S², S⁴, S⁶ and S⁸. As here shown, each signal is located adjacent the junction of two track sections, although this exact location is not essential. Each signal is of the three-position type, arranged to indicate "Stop," "Caution" and "Proceed."

Each signal S is controlled by a line relay which is designated by the reference character A with the same exponent as that of the signal which it controls.

Each signal is provided with a caution circuit and a proceed circuit. Referring particularly to signal S⁵, the caution circuit is from one terminal B of a suitable source of current, through front point of contact 14 of relay A⁵, wire 15, operating mechanism of signal S⁵, wire 16, and contact 17 of relay A⁵ to the other terminal C of the same source of current. The proceed circuit is from terminal B through the front point of contact 14, wire 18, polarized contact 19 of relay A⁵, wire 20, and thence as before to terminal C. It will be seen that this proceed circuit is closed only when relay A⁵ is energized in such direction as to close contact 19, which direction I will term the normal energization of this relay.

The control circuits for each of the signals are similar to those for signal S⁵, and hence they need not be traced in detail herein.

The line relay A⁸ for signal S⁸ is provided with a circuit which passes from terminal B (see Fig. 1^c) of a suitable source of current, through a pole-changer P⁶ operated by signal S⁶, wires 21 and 22, contact 23 of relay A⁶, wire 24, contact 25 of track relay T⁸, wire 26, contact 27 of track relay T⁹, wire 28, winding of relay A⁸, common wire O, wire 30 and pole-changer P⁶ to the terminal C of the same source of current. This circuit, then, is controlled by track relays T⁸ and T⁹, and by the line relay A⁶ for signal S⁸.

Line relay A⁶ is controlled by track relays T⁷, T⁶, T⁵ and T⁴, and by a pole-changer Q' or a pole-changer Q² according as a relay M⁴ is de-energized or energized. Pole-changers Q' and Q² are both controlled by signal S⁴, and these pole-changers operate in the manner set forth in the legend applied to Fig. 1^b of the drawing. When relay M⁴ is de-energized, the circuit for re-

lay A^6 is from terminal B of a suitable source of current through pole-changer Q' , wire 31, back contact 32 of relay M^4 , wire 33 contact 34 of track relay T^4 , wire 35, contact 36 of track relay T^5 , wire 37, contact 38 of track relay T^6 , wire 39, contact 40 of track relay T^7 , wire 41, relay A^6 , common wire O, back contact 42 of relay M^4 , wire 43, and pole-changer Q' to terminal C of the 10 same source of current. When relay M^4 is energized, the circuit for relay A^6 is the same as that just traced, except that it includes the front points of contacts 32 and 42 of relay M^4 , wires 76 and 77, and pole-changer Q^2 instead of pole-changer Q' .

Relay A^4 , which controls signal S^4 is provided with a circuit which passes from terminal B of a suitable source of current through pole-changer P^2 (see Fig. 1^a) operated by signal S^2 , wire 58, contact 59 of track relay T' , wire 60, contact 61 of track relay T^2 , wire 62, contact 63 of track relay T^3 , wire 64, winding of relay A^4 , common wire O', wire 78, and pole-changer P^2 to terminal C of the same source of current.

Relay A^2 , for signal S^2 , is controlled by apparatus in the stretch of track (not shown) lying to the west of siding G, in 30 the same manner as relay A^8 is controlled by the apparatus in the stretch between sidings G and H.

The circuit for line relay A^8 is provided with a branch around contact 23 of line 35 relay A^6 , which branch is from wire 21, through wire 44, contact 45 of an auxiliary relay X^6 and wire 46 to wire 24. Relay X^6 is provided with a pick-up circuit which passes from terminal B, through contact 47—47^a operated by signal S^6 , wire 48, back contact 49 of track relay T^8 , wires 50 and 51, and winding of relay X^6 to terminal C. Inasmuch as contact 47—47^a is closed only when signal S^6 is in proceed or the caution 40 position, it follows that this relay can be energized only while a westbound train is passing along the track. Relay X^6 is provided with a holding circuit which passes from terminal B, through back contact 52 of track relay T' , wire 53, wire 54, contact 55 of relay X^6 , wires 56 and 51, and winding of relay X^6 to terminal C. This holding circuit is provided with a branch around contact 52 of track relay T' , which branch 50 is from terminal B, through contact 47—47^b and wire 57 to wire 54. Inasmuch as contact 47—47^b is closed while signal S^6 is in the stop position, it follows that when auxiliary relay X^6 has once become energized, 55 it will remain energized as long as signal S^6 indicates stop.

Each of the other auxiliary relays X is controlled in the same manner as relay X^6 .

Relay M^4 is provided with a pick-up circuit which passes from terminal B of a

suitable source of current (adjacent signal S^4), through wire 65, contact 66 operated by signal S^4 , wire 67, back contact 68 of line relay A^4 , polarized contact 69 of relay A^4 , wires 70 and 71, and winding of relay M^4 to terminal C of the same source of current. Contact 66 is closed momentarily while signal S^4 is between the caution and the stop positions. It will be seen, therefore, that relay M^4 is energized when a train 75 moving toward the west enters track section 6—7, provided that relay A^4 is normal, because contacts 66 and 68 are then closed simultaneously and contact 69 remains closed, but is not energized when a train 80 passes over the track in the opposite direction because contact 69 is then opened before 66 and 68 close. This relay is provided with a holding circuit which passes from terminal B, through wire 65, contact 72, wire 73, contact 74 of relay M^4 , wires 75 and 71, and winding of relay M^4 to terminal C. This circuit is closed as long as signal S^4 indicates stop or caution, but is opened when the signal indicates proceed. 90

The operation of the westbound signals is as follows:

When a train moving toward the east passes the point in the stretch west of siding G corresponding to point 7, it will cause 95 signal S^2 to move to the stop position. The consequent reversal of pole-changer P^2 causes line relay A^4 to reverse, whereupon signal S^4 moves to the caution position. This movement of signal S^4 reverses pole-changer Q' and since relay A^6 is now controlled by this pole-changer, this relay reverses, so that signal S^6 moves to the caution position. Signal S^8 remains in the proceed position. 100

As the eastbound train passes point 4 it opens the circuit for relay A^4 at contact 59 of track relay T' , so that signal S^4 moves to the stop position, but this does not affect signals S^6 and S^8 . When the train passes signal S^4 , it opens the circuit for relay A^6 at track relay T^4 , so that signal S^6 moves to the stop position. The opening of relay A^6 causes relay A^8 to be opened so that signal S^8 moves to the stop position. When the entire train has passed signal S^4 , this signal returns to the proceed position, provided that it is not affected by a second train to the west of this signal. When the train passes signal S^6 , this signal likewise returns to the proceed position, and when the train passes signal S^8 a similar operation occurs. 115

When a westbound train passes signal S^8 , it, of course, places this signal at stop, and when the train passes signal S^6 the latter signal is also caused to move to the stop position. As this train passes signal S^6 , it causes relay X^6 to become energized, so that after the rear of the train has 120 passed out of section 10—11, line relay A^8 130

becomes energized in the reverse direction, whereupon signal S^8 moves to the caution position. As the train passes signal S^4 it causes this signal to assume the stop position, 5 and causes relay M^4 to become energized. Signal S^6 then returns to the caution position and signal S^8 returns to the proceed position. As the train passes signal S^2 , this 10 signal assumes the stop position and after the train passes out of section 4-5 signal S^4 returns to the caution position. Relay A^6 now being under the control of pole-changer Q^2 , this relay becomes energized in the normal direction, so that signal S^6 returns to the proceed position. 15 When the train passes the signal to the west of signal S^2 , signal S^2 returns to the caution position, so that signal S^4 returns to the proceed position.

20 The signals governing traffic from west to east, are controlled in exactly the same manner as those governing traffic from east to west, and, consequently, a detailed explanation of the control and operation of 25 the eastbound signals is not necessary.

Located in the rear of each signal are two traffic controlling devices which, as here shown, are in the form of ramps, and will hereinafter be referred to as such. The 30 two ramps immediately in the rear of each signal are designated by the reference characters C and D with suitable exponents, and may be termed the home and distant ramps respectively. The reference character C for each home ramp is provided with the same exponent as that of the adjacent signal because, as will appear hereinafter, this ramp is normally controlled directly by this signal. The reference character D for each distant ramp is provided with the same exponent as that of the signal next in advance of the adjacent signal because, as will appear hereinafter, this ramp is normally controlled in accordance with the indication given by such signal in advance.

45 The control of the ramps is as follows:

The supply of current to each home ramp C is governed by a ramp relay which is 50 designated by the reference character E with the same exponent as that applied to the corresponding ramp. Each of these relays (see E^4 and E^5) comprises a neutral armature contact 79 and a polar armature contact 80, and the control of the ramp is 55 such that the ramp is energized by current of normal or reverse polarity according as the relay is energized in normal or reverse direction. Considering ramp C^5 , for example, when the corresponding relay E^5 is 60 energized in normal direction, the circuit for this ramp is from positive terminal of battery 81, through contact 80, contact 79, ramp C^5 , thence through the governing apparatus on the train to track rail 2^a, and 65 then through wire 82 to the middle point

of battery 81. When relay E^5 is energized in the reverse direction, the circuit is the same except that the negative terminal of battery 81 is connected with the ramp.

The controlling circuits for each ramp 70 C and D are the same as those just pointed out for ramp C^5 .

The relay E for each home ramp C is normally controlled by a contact J operated by the adjacent signal, which contact is 75 closed when the signal indicates proceed or caution, but open when the signal indicates stop. Considering relay E^5 , for example, the normal controlling circuit is from terminal B of a suitable source of current, 80 through contact J⁵ operated by signal S^5 , wires 83 and 84, winding of relay E⁵, wire 85, and common wire O, to terminal C of the same source of current. The polarity of the current thus supplied to relay E⁵ is 85 normal, so that this relay is energized by current of normal polarity when signal S^5 indicates proceed or caution, but so far as the circuit thus far traced is concerned, the relay is de-energized when signal S^5 indicates stop.

The circuit for relay E⁵ is provided with a branch around contact J⁵ of signal S^5 , which branch is closed when auxiliary relay X⁶, corresponding to the opposing signal S^6 , is energized. The circuit for relay E⁵ is then from terminal B, through pole-changer Q', (see Fig. 1^b), wire 31, back point of contact 32 of relay M⁴, wire 33, contact 34, of track relay T⁴, wire 35 wire 100 86, contact 87 of relay X⁶, wire 88, wire 84, winding of relay E⁵, wire 85, and common wire O to terminal C of the same source of current. Under this condition it will be seen that ramp C⁵ is controlled 105 by traffic conditions to the west of this ramp instead of by traffic conditions to the east. It will be observed that auxiliary relay X⁶ is energized by a train moving toward the west. The reason for this 110 alternative control of ramp C⁵ will be pointed out hereinafter.

Relay F⁵, which controls the distant ramp D⁵, is normally controlled by line relay A³, the circuit being from the positive terminal 115 of a battery 95 (Fig. 1^b) through polar contact 100 of relay A³, wire 89, contact 68, wire 90, back point of contact 91 of auxiliary relay X⁴, wire 92, relay F⁵, wire 93, common wire O' and wire 96 to the middle 120 point of battery 95. When relay A³ is energized in normal direction, relay F⁵ is energized in such direction as to supply current of normal polarity to ramp D⁵, but when relay A³ is reversed, contact 100 is 125 shifted to the negative terminal of battery 95, whereby relay F⁵ is also reversed so that current of reverse polarity is supplied to ramp D⁵. When relay A³ is open, relay F⁵ is also open so that the ramp is de-energized. 130

The circuit for ramp relay F^5 is provided with a branch around the contacts of relay A^3 , which branch is closed when auxiliary relay X^4 is closed. The circuit for relay F^5 is then from terminal B through pole-changer P^2 (Fig. 1^a), wire 58, contact 59 of track relay T' , wire 60, contact 61 of track relay T^2 , wire 62, wire 94, front point of contact 91 of auxiliary relay X^4 , wire 92, relay F^5 , wire 93, and common wire O' to terminal C. When relay X^4 is energized, then, that is, when a train passes signal S^4 moving toward the west, ramp D^5 is placed under the control of traffic conditions to the west of the ramp.

The control of each of the ramp relays is the same as the control of relays E^5 and F^6 , except in the case of relays E^4 and E^7 . Relay E^4 is normally controlled by contact J^4 operated by signal S^4 , but when auxiliary relay X^3 becomes energized the ramp relay E^4 is placed under the control of line relay A^5 . Similarly, ramp relay E^7 is normally controlled by contact J^7 of signal, but is placed under the control of line relay A^6 when auxiliary relay X^8 becomes energized.

Before explaining the operation of the ramps, it should be pointed out that the trackway apparatus herein shown is intended for co-operation with train-carried apparatus, arranged as follows: Each locomotive is equipped with two contact shoes, one on each side, so that as the locomotive passes along the track, the train governing apparatus is affected by each ramp regardless of the side of the track on which the ramp is located and regardless of whether the locomotive is moving forward or backward. When the locomotive passes over a ramp which is energized by current of normal polarity, the train governing apparatus is affected to permit the train to travel at full speed, such, for example, as 65 miles per hour, until a different indication is received from the trackway. When the locomotive passes over a ramp which is energized by current of reverse polarity, the train governing apparatus is affected to reduce the speed of the train to 35 miles per hour and to prevent subsequent increase of speed above this value until a new indication is received from the trackway. When the locomotive passes over a ramp which is deenergized, the train governing apparatus is affected to bring the train to a full stop and to prevent subsequent progress of the train until suitable action is taken by the engineer after the train has come to rest. The train may then proceed at a speed not exceeding a low value, such as 10 miles per hour, until a new indication is received from the trackway.

The operation of the apparatus in so far as the ramps are concerned, is as follows:

65 I will first assume that the stretch of track

here shown is unoccupied and that an east-bound train enters this stretch. The train will receive a full speed or proceed indication at ramp C' , because signal S' is in the proceed position. A similar indication will be received at ramp D^3 , because line relay A' is energized in the normal direction. Auxiliary relay X' becomes energized as the train enters section 4-5, so that ramp D^6 is placed under the control of track relays T^3 and T^4 and pole-changer P^3 . This ramp is, consequently, energized by current of normal polarity, so that it gives a proceed or full speed indication when it is passed by the train. Ramp C^2 is under the control of the same elements as ramp D^3 for the same reason, that is, for the reason that auxiliary relay X' is energized, and, consequently, the train receives a proceed or full speed indication when it passes over this ramp. At ramp C^3 a full speed indication is received, because this ramp is under the control of signal-operated contact J^3 , and signal S^3 is in the proceed position. Similarly, at ramp D^5 a full speed indication is received, because line relay A^3 is energized in normal direction. The operation of the apparatus during the passage of this train through the remainder of the stretch will be clear from the foregoing without further explanation.

I will now assume that track section 8-9 is occupied by an eastbound train which is at rest or is moving very slowly, and that a following eastbound train enters the stretch of track shown in the drawings. Line relay A^3 is now de-energized, so that signal S^3 is in the stop position, and line relay A' is energized in the reverse direction, so that signal S' is in the caution position. At ramp C' the train receives a full speed indication, owing to the fact that contact J' , operated by signal S' , is closed. At ramp D^3 the train receives a medium speed indication, because relay F^3 is energized in the reverse direction, due to the fact that relay A' is reversed. The speed of the train is, consequently, reduced to 35 miles per hour after passing this ramp. The medium speed indication is repeated at ramp D^6 , because relay F^6 is then under the control of pole-changer P^3 (auxiliary relay X' being energized), and this pole-changer is reversed. The same indication is again received at ramp C^2 for the same reason. At ramp C^3 a stop indication is received, because the circuit for ramp relay E^3 is now open at contact J^3 due to the fact that signal S^3 is in the stop position. The train will, therefore, be brought to a stop before reaching signal S^3 , but may again proceed at low speed after suitable action on the part of the engineer.

I will next assume that the first train passes out of section 8-9 into section 9-10 while the second train is between ramps C^3 and

and D^5 . It will be remembered that the second train received a stop indication at ramp C^3 , due to the fact that signal S^3 was in the stop position, so that contact J^3 was 5 open. The movement of the first train past signal S^5 , however, permits relay A^3 to become energized in the reverse direction, so that signal S^3 returns to the caution position. It would, of course, be unnecessary and 10 undesirable to give the second train a stop indication at ramp D^5 under these circumstances. Ramp D^5 is now energized by current of reverse polarity, because the circuit for relay F^5 is closed at contact 68 of relay 15 A^3 , contact 100 of this relay being, of course, in the reverse position. The result is that a medium speed indication is received at ramp D^5 . A similar indication is received at ramp D^2 and again at ramp C^4 , but a 20 stop indication is received at ramp C^5 for reasons which will be apparent from the foregoing explanation.

I will now assume that a westbound train passes signal S^8 , and that immediately thereafter an eastbound train passes point 4. The westbound train will place signal S^3 at stop, so that the eastbound train will receive a caution indication at ramp D^3 and the same indication again at ramp D^0 . At ramp 30 C^3 , however, the eastbound train will receive a stop indication, because the circuit for relay E^3 for this ramp is open at contact J^3 of signal S^3 . The eastbound train will, consequently, be brought to a stop before reaching signal S^8 .

The operation of the apparatus during other conditions of train movements will be understood from the foregoing discussion.

Although I have herein shown and described only one form of trackway apparatus embodying my invention, it is understood that various changes and modifications may be made therein within the scope of the appended claims without departing from the 45 spirit and scope of my invention.

Having thus described my invention, what I claim is:

1. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay 55 energized as long as such signal indicates stop, a traffic controlling device adjacent each signal, a main circuit for each device controlled by the line relay for the corresponding signal and by a back contact of 60 the auxiliary relay for an adjacent opposing signal, and an auxiliary circuit for each device controlled by a front contact of the last-mentioned auxiliary relay and by means located in the rear of the signal corresponding to the device.
2. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, 80 means for energizing each auxiliary relay when a train passes the corresponding signal moving in the direction in which such signal governs traffic and for keeping the auxiliary relay energized as long as such signal indicates stop, a traffic controlling device adjacent each signal, a relay F for each device, a main circuit for each relay F controlled by the line relay for the corresponding signal and by a back contact of the auxiliary 85 relay for an adjacent opposing signal, and an auxiliary circuit for each relay F controlled by a front contact of the last-mentioned auxiliary relay and by means located in the rear of the signal corresponding to the device which such relay controls.
3. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay 100 energized as long as such signal indicates stop, a traffic controlling device for each signal, a main control circuit for each device governed by the line relay for the corresponding signal, an auxiliary control circuit for each device governed by means located 105 in the rear of the signal corresponding to the device which such relay controls.

in the rear of the corresponding signal, and means for each device for placing the device under control of said main circuit or of said auxiliary circuit according as the auxiliary relay for an adjacent opposing signal is de-energized or energized.

4. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay energized as long as such signal indicates stop, a traffic controlling device for each signal, means for normally controlling each device by the line relay for the corresponding signal, and means for each device controlled by the auxiliary relay for an opposing signal for removing the device from control by said line relay and placing it under control of the line relay for an opposing signal in the rear of the signal corresponding to the device.

5. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay energized as long as such signal indicates stop, a traffic controlling device for each signal, means for normally controlling each device by the line relay for the corresponding signal, and means for each device controlled by the auxiliary relay for an adjacent opposing signal and operative when such auxiliary relay is energized to remove the device from control by said line relay and to place it under control of means in the rear of the signal to which the device corresponds.

6. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay energized as long as such signal indicates stop, a traffic controlling device for each signal, means for normally controlling each device by the line relay for the corresponding signal, and means for each device controlled by the auxiliary relay for an adjacent opposing signal and operative when such auxiliary relay is energized to remove the device from control by said line relay.

7. In combination, a stretch of railway track, signals located at intervals for governing traffic in one direction through said stretch, other signals located at intervals for governing traffic in the other direction through said stretch, a line relay for each signal, track circuits for the stretch including track relays for controlling said line relays, means for controlling each line relay by the line relay for the signal next in advance governing traffic in the same direction, an auxiliary relay for each signal for removing the corresponding line relay from its control of the line relay in the rear, means for energizing each auxiliary relay when a train passes the corresponding signal moving in the direction in which such signal indicates stop, a traffic controlling device for each signal, means for normally controlling each device by the line relay for the corresponding signal, and means for each device controlled by the auxiliary relay for an adjacent opposing signal and operative when such auxiliary relay is energized to remove the device from control by said line relay, and to place it under control of a track relay which is not opened until a train moving in the direction opposite to that in which the device governs traffic has passed the device.

8. In combination, a stretch of railway track, signals located at intervals for governing traffic in one direction through said stretch, other signals located at intervals for governing traffic in the other direction

- through said stretch, a line relay for each signal, track circuits for the stretch including track relays, a line circuit for each line relay controlled by the track relay or relays between the corresponding signal and the signal next in advance governing traffic in the same direction and by the line relay for the latter signal, an auxiliary relay for each signal for removing the corresponding line relay from its control of the line relay in the rear, means for energizing each auxiliary relay when a train passes the corresponding signal moving in the direction in which such signal governs traffic and for keeping the auxiliary relay energized as long as such signal indicates stop, a traffic controlling device for each signal, means for normally controlling each device by the line relay for the corresponding signal, and means for each device controlled by the auxiliary relay for an adjacent signal governing traffic in the opposite direction and operative when such auxiliary relay is energized to remove the device from control by said line relay and to place it under the control of a portion of the line circuit for the line relay of said adjacent signal.
9. In combination, a section of railway track, a signal located at one end of said section for governing traffic into the section and arranged to indicate stop, caution or proceed, a line relay responsive to reversals of current for controlling said signal, means for supplying current of normal or reverse polarity to said relay, a track circuit for said section for controlling said relay, two traffic controlling devices adjacent said signal, means for energizing one of said devices by current of normal or reverse polarity according as said line relay is energized in normal or reverse direction and for de-energizing said device when the relay is de-energized, means for energizing the other device when said signal indicates proceed or caution but not when the signal indicates stop, and means controlled by a train in said section moving towards said signal for removing said devices from control by said relay and signal and for placing said devices under control of means in the rear of the devices.
10. In combination, a section of railway track, a signal located at one end of said section for governing traffic into the section and arranged to indicate stop, caution or proceed, a line relay responsive to reversals of current for controlling said signal, means for supplying current of normal or reverse polarity to said relay, a track circuit for said section for controlling said relay, two traffic controlling devices adjacent said signal, means for energizing one of said devices
- by current of normal or reverse polarity according as said line relay is energized in normal or reverse direction and for de-energizing said device when the relay is de-energized, means for energizing the other device when said signal indicates proceed or caution but not when the signal indicates stop, a stick relay, means controlled by said stick relay when energized for removing said devices from control by the line relay and signal and for placing said devices under control of means in the rear of the devices, means controlled by a train in said section moving towards said signal for energizing said stick relay, and means for keeping said relay energized until the train has passed said devices.
11. In combination, two successive traffic controlling devices each normally serving to govern eastbound traffic only, a third traffic controlling device normally serving to govern westbound traffic only, each of said devices being individually capable of giving aboard a train all the indications desired in the system depending on the electrical condition of the device, and means operating automatically when an eastbound train approaches said third device to cause such third device to give the same indication aboard the train as that given by the first eastbound device encountered by the train, thereby preventing said third or westbound device from interfering with eastbound traffic.
12. In combination, a plurality of successive traffic controlling devices each normally serving to govern eastbound traffic only, a plurality of successive traffic controlling devices staggered with relation to the eastbound devices and each normally serving to govern westbound traffic only, each of said devices being individually capable of giving aboard a train all the indications desired in the system depending on the electrical condition of the device, and means operating automatically when a train moving in either direction approaches an opposing device to cause such device to give the same indication aboard the train as was given by the last-encountered device corresponding to the direction in which the train is moving, thereby preventing the devices governing traffic in either direction from interfering with traffic in the other direction.
- In testimony whereof I affix my signature in presence of two witnesses.
- RONALD A. McCANN.
- Witnesses:
- WALTER P. NEUBERT,
A. L. VENCILL.
